RAIN WATER CONTAINER

Andrew H. De Groff, Little Genesee, N. Y.

Application February 16, 1939, Serial No. 256,800

1 Claim. (Cl. 220—1)

This invention relates to rain water containers and has for an object to provide for a device of this character which may be located in tracts of timber to accumulate a supply of rain water for use in combating forest fires.

A further object of the invention is to provide for a device of this character which is of such construction as to substantially eliminate the hazard of freezing while at the same time manual attention will be reduced to a minimum.

A further object is to provide a device of this character which will be formed of a few strong, simple and durable parts, which will be inexpensive to manufacture, and which will not easily get out of order.

With the above and other objects in view the invention consists of certain novel details of construction and combinations of parts hereinafter fully described and claimed, it being understood that various modifications may be made within the scope of the appended claim.

In the accompanying drawing forming part of this specification,

Figure 1 is a vertical sectional view of a rain water container constructed in accordance with the invention.

Figure 2 is a top plan view of the container with a portion of the cover broken away.

Referring now to the drawing in which like characters of reference designate similar parts in the various views, the invention is shown to include a tank 10 in the form of an inverted cone, the wall of the tank being formed with a plurality of longitudinal corrugations 11 extending from the apex to the upper edge of the tank to allow for expansion and contraction due to weather changes.

The tank is supported upon a plurality of standards 12 preferably three in number, arranged in the form of a triangle and surmounted by a ring 13. The conical tank is disposed within the ring with its lowermost point being supported in a base 14.

The open top of the tank is closed by a shallow conical cover 15 which is provided with concentric rows of perforations 16 nearest its lowest peripheral portion. The cover is provided above the openings with a struck-out annular trough 17 which is concentric with the apex of the cover and reinforces the cover against distortion. The trough is provided at the bottom with perforations 18. The perforations in the trough and in the cover proper permit the straining of rain water from the cover into the tank through

branches or other debris which may accumulate on the cover in the forest. The cover is curved upwardly at the lower peripheral edge thereof to provide a second trough 19 which rests upon the top edge of the tank and the trough 19 is provided with a depending flange 20 which surrounds and overlaps the top edge of the tank and prevents accidental dislodgement of the cover from high winds or other causes.

10 A container 21 for fire fighting chemicals, or the like, is mounted on the tank through the medium of a bar bracket 22 which is secured to the standards in any preferred manner.

15 The cover is provided adjacent its lower edge with a relatively large opening 23 which receives a siphon tube 24 the lower end of which extends to nearly the bottom point of the tank. Also the tank is provided near its upper edge with an overflow opening 25.

In operation during periods of rain fall, rain water will accumulate in containers of the above-described type, located at various predetermined localities in wooded areas. In case of fire the water supply is thus available at localized points for immediate use by the fire fighters.

From the above description it is thought that the operation of the invention be fully understood without further explanation.

What is claimed is:

30 A rain water storage container for forest fire fighting comprising, a tank in the form of an inverted cone, the wall of which is formed with a plurality of longitudinal corrugations extending from the apex to the upper edge of the tank to allow for expansion and contraction, a cover in the form of a shallow cone closing the open top of the tank provided with perforations near the lowest peripheral portion thereof, a struck-out trough in the cover concentric with the apex of 35 the cover reinforcing the cover against distortion, there being perforations in the bottom of the trough, the perforations in the trough and in the cover permitting straining of rain water from the cover into the tank through branches or other debris which may accumulate on the cover in the forest, a second trough formed by a curved peripheral edge portion of the cover resting upon the top edge of the tank, and a depending flange on the second-named trough surrounding and overlapping the top edge of the tank to prevent 40 accidental dislodgement of the cover from high winds or other causes.
